ADJUSTABLE LAMP STANDARD

Eugene Schwarz, Alexandria, Ind., assignor to
 The Mantle Lamp Company of America, Chi-
 cago, Ill., a corporation of Illinois

Application January 21, 1933, Serial No. 652,859

4 Claims. (Cl. 248—161)

The invention relates to adjustable electrical-lamp standards of a type wherein one part of a standard telescopes within another part thereof, objects of said invention being to facilitate vertical movements of the lamp-carrying element, to avoid wearing or abrasion of the electrical conductor which supplies the lamp with its current, to render easy the production and the assembling of the component elements of the standard, as well as to secure a rigid union of said elements, and to give to the standard a desired ornamental appearance.

The invention is illustrated in the accompanying drawing, in which—

15 Figure 1 is a view in elevation of the entire standard, parts thereof being broken away to reveal internal features of construction;

20 Figure 2 is a similar view showing the adjustable element of the standard in its lowest position;

Figure 3 shows parts of the device, somewhat enlarged;

25 Figure 4 is a vertical sectional view showing the construction of the base of the standard, and

Figure 5 is a vertical sectional view, showing a modification.

Referring to Figures 1 and 2 of the drawing, 1 is the base of the standard, through which the insulated conductors 2 extend, these conductors 30 being provided with the usual plug 3, and said base having feet 4 between any two of which said conductors may lie. Supported by and extending upward from the base 1 is a tube 5 constituting the fixed part of the standard relative- 35 ly to which telescopes the hollow vertically-adjustable element 6 carrying the casting 7 and the arm 8 on which the bulb 9 is supported. A tubular casting 10 surmounts the upper end of said tube 5, and this casting is provided with a thumb screw 11 which engages a groove 11a in the outer wall of the tube 6 and operates to hold said tube 40 in any desired elevated position.

Said casting may also be provided with a set screw 11b to prevent turning of said vertically-adjustable element 6 when the thumb screw 11 is withdrawn. The tube 5 may be united to said casting 10 by inserting its upper end in the mold in which said casting is formed, said upper end being provided with irregularities 10a with which the metal constituting said casting may interlock.

The casting 7 and the tube 6 extend one into the other, as shown in Figure 1 and are fixedly 55 united in any suitable manner, but, in order to

enable them to be readily assembled and separated, their union may be effected by the means shown in Figure 5 wherein an inner tube 12, which acts as a tie-rod, is suitably secured at its upper screw-threaded end 12a in said casting 7, and at its lower end carries a nut 13 having an external flange 13a on which said tube 6 rests. By tightening said nut said tube 6 will be forced upward against the lower surface of said casting 7 and thus securely held in position.

The lowered position of said vertically-adjustable element 6 is determined by the top of the ornamental tubular casting 10 on which the ornamental tubular casting 7 then rests, while the highest position of said element 6 is determined 15 by the screw 11 with which the lower end 15 of the groove 11a engages.

The lower end of the fixed tube 5 has ribs 16 and is surrounded by a casting 17 constituting a part of said base 1. Other parts of said base 20 are hollow castings 18, 19 and 20, all of which are held together by a tube 21 having exterior ribs 22 which engage the metal of said casting 17, and having also a screw-threaded lower end 23 which engages an interior screw-thread of the 25 casting 20.

The conductors 2 extend upward through the fixed tube 5, within which they are formed into a coil 2a within which is disposed a reversely-coiled spring 24 which opposes the elongation of 30 the coil 2a and prevents it from uncoiling. This spring 24 has conically-coiled ends 25 which firmly grasp and indent the rubber coating 26, to thereby hold said spring 24 and said coil 2a in proper relations to each other.

The convolutions of the coil 2a are covered with a thin coating of rubber 26 instead of fabric or metal, the reason for using rubber being that rubber, unlike fabric, resists abrasion, and, unlike metal, being flexible, does not materially resist the required elongation or contraction of the coiled conductor.

In assembling the parts of the base, molten metal is poured into a mold and around the ribbed end 16 of the fixed tube 5, and also around 45 the ribbed portion 22 of the tube 21, thus producing the casting 17 which unites said fixed tube 5 and said tube 21. The fixed element or tube 5 is, preferably, a very thin tube which is incapable of being screw-threaded, although it may 50 be readily provided with the ribs 16 or similar irregularities which will engage the metal of the casting 17. The tube 21 which is considerably smaller than the tube 5, extends upward within said tube 5 to such a point that the molten metal 55

will not overflow into it, although it will rise between the concentric ends of said tubes and add strength at the point where strength is required. The thin tube 5 if especially weak might yield to strains if not thus reinforced. The assembling of the parts is completed by placing the elements 18, 19 and 20 of the base 1 in their proper positions and screwing the lower end of the tube 21 into the element 20, and by fixedly attaching the upper end of the fixed tube 5 to the casting 10 in any usual manner.

Having thus described my invention, what I claim is:

1. An adjustable lamp standard, including a base, a fixed tubular element rising from said base, a vertically-adjustable tubular element telescoping with the said fixed tubular element, and rubber-coated conductors having coils secured to a reversely-coiled spring and disposed within one of said tubular elements.
2. An adjustable lamp standard, including a base, a fixed tubular element rising from said base, a casting surmounting and interlocked with said tubular element, a vertically-adjustable tubular element telescoping with said casting, a

head surmounting said vertically-adjustable tubular element, a tubular tie-rod disposed within said vertically-adjustable tubular element and engaging said head, a nut secured to the lower end of said tie-rod and directly engaging the lower end of said vertically-adjustable tubular element, and conductors extending through said tubular tie-rod.

3. An adjustable lamp standard, including a tubular element, a coiled conductor disposed within said tubular element, and a reversely-coiled spring attached at its upper and lower ends to said coiled conductor for preventing said coiled conductor from uncoiling.

4. A lamp standard including a thin metal tube having an annular rib at its lower end, a smaller tube having an annular rib and extending upward into the lower end of said thin metal tube, and a casting surrounding a part of said smaller tube and engaging the rib thereof, the upper end of said casting being disposed around the rib of said thin metal tube and extending into the space between the lower end of said thin metal tube and said smaller tube.
